VALET STAND

Roderic M. Koch, 10 S. 11th Ave., Evansville, Ind.

Filed Aug. 14, 1962, Ser. No. 71,283

Term of patent 14 years

(Cl. D33—8)

FIG. 1

FIG. 2

FIG. 3

FIG. 4

FIGURE 5 is a sectional view taken on the line 5—5 of FIG. 1.

I claim:

The ornamental design for a valet stand, as shown and described.
